UNITED STATES PATENT OFFICE.

BENJAMIN V. GINTZ, OF AKRON, OHIO.

DESIGN FOR A BICYCLE-TIRE.

SPECIFICATION forming part of Design No. 27,221, dated June 15, 1897.

Application filed January 11, 1897. Serial No. 618,809. Term of patent 7 years.

To all whom it may concern:

Be it known that I, BENJAMIN V. GINTZ, a citizen of the United States, residing at Akron, in the county of Summit and State of Ohio, 5 have invented and produced a certain new and original Design for Treads for Bicycle-Tires, of which the following is a specification.

My invention has relation to the production 10 of a new and original design for the outer periphery or circumference of a bicycle-tire and commonly known as the "tread" portion thereof.

In the accompanying drawings, in which 15 reference-numerals indicate like parts in the different figures, Figure 1 is a plan of the tread portion or outer periphery of a bicycle-tire, showing my design; Fig. 2, a side elevation of the same. Fig. 3 shows my complete 20 tire.

My design consists in a raised geometric figure on the outer periphery or tread portion

of a tire 1, the outlines of which will appear in Fig. 1, and the thickness of the raised figure will appear in Fig. 2; and the figure I 25 choose to employ in my design is a series of ellipses 2 and diamonds 3, alternating with one another and substantially touching each other.

Only the edges of the figure are raised, the 30 center being in the same plane with the balance of the tire. This outline figure is integral with the tire and consists of a series of raised ridges arranged as hereinbefore described.

What I claim is—

The design for a bicycle-tire substantially as shown and described.

In testimony that I claim the above I hereunto set my hand.

BENJAMIN V. GINTZ.

In presence of—

C. E. HUMPHREY,
C. P. HUMPHREY.
